CLAIM

The ornamental design for an assembly of an xy-coupling supporting a carrier arm holding a housing containing one or two microscope bodies, as shown and described.

DESCRIPTION

FIG. 1 is a right side elevation view of our new design of an assembly of an xy-coupling supporting a carrier arm holding a housing containing one microscope body;

FIG. 2 is a front side elevation view of said assembly of FIG. 1;

FIG. 3 is a left side elevation view of said assembly of FIG. 1;

FIG. 4 is a rear elevation view of said assembly of FIG. 1;

FIG. 5 is a top plan view of said assembly of FIG. 1;

FIG. 6 is a bottom plan view of said assembly of FIG. 1;

FIG. 7 is a perspective view of said assembly of FIG. 1;

FIG. 8 is a right side elevation view of another embodiment of our new design of an assembly of an xy-coupling supporting a carrier arm holding a housing containing two microscope bodies;

FIG. 9 is a front side elevation view of said assembly of FIG. 8;

FIG. 10 is a left side elevation view of said assembly of FIG. 8;

FIG. 11 is a rear side elevation view of said assembly of FIG. 8;

FIG. 12 is a top plan view of said assembly of FIG. 8;

FIG. 13 is a bottom plan view of said assembly of FIG. 8; and,

FIG. 14 is a perspective view of said assembly of FIG. 8.

The broken lines form no part of the claimed design.
